DESIGN FOR A TOY GUN

Samuel I. Berger, Newark, N. J.

Application September 24, 1945, Serial No. 122,293

Term of patent 14 years

(Cl. D34—15)

To all whom it may concern:

Be it known that I, Samuel I. Berger, a citizen of the United States and residing at Newark, in the county of Essex and State of New Jersey, have invented a new, original, and ornamental Design for a Toy Gun, of which the following is a specification, reference being had to the accompanying drawing, forming part thereof, and in which

Fig. 1 is a top plan showing my new design for a toy gun,

Fig. 2 is a side elevation thereof, and

Fig. 3 is an end elevation.

I claim:

The ornamental design for a toy gun, substantially as shown.

SAMUEL I. BERGER.
